US00D917373S

(12) **United States Design Patent** (10) **Patent No.:** **US D917,373 S**
(45) **Date of Patent:** **** Apr. 27, 2021**

(54) **CATALYTIC CONVERTER COVER**

(71) Applicant: **Richard Blake Tamagni**, Roseville, CA (US)

(72) Inventor: **Richard Blake Tamagni**, Roseville, CA (US)

(**) Term: **15 Years**

(21) Appl. No.: **29/728,585**

(22) Filed: **Mar. 19, 2020**

(51) LOC (13) Cl. **12-16**

(52) U.S. Cl.

USPC **D12/400**

(58) **Field of Classification Search**

USPC D15/66-78; D8/323, 349, 356, 394, 381, D8/354, 366, 382; D12/412, 193, 180, D12/223, 196, 167, 400, 190, 90, 91, 92; D9/537, 545, 549; D24/216, 223-227, D24/229-232; D6/300-308; D7/300, D7/305, 306, 307, 308, 312, 313, 391, D7/397, 541, 550.1, 553.1, 553.2, 553.3, D7/555.589, 590, 601, 602, 701, 388, D7/698, 387, 402, 407, 408, 409, 543, D7/549, 586, 699; D13/103, 107, 108, D13/110, 118, 184, 199; D29/10, 11, 99, D29/100, 101.2, 101.3, 122; D14/239, D14/371, 136, 374, 375, 376, 377, 238

CPC ... B29C 64/118; F01N 13/18; F01N 13/1805; F01N 13/1822; B60R 25/20; F16M 11/10

(57) **CLAIM**

The ornamental design for a catalytic converter cover, as shown and described.

DESCRIPTION

FIG. 1 is a front, top perspective view of the catalytic converter cover, showing my new design;

FIG. 2 is a rear, top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a rear, top, right side perspective view thereof; and, FIG. 10 is a bottom, front perspective view thereof, shown in a position of use.

The broken lines within the claim, illustrate portions of the catalytic converter cover which form no part of the claimed design. The broken lines in FIG. 10 illustrating an automobile, depict environmental structure that forms no part of the claimed design.

1 Claim, 5 Drawing Sheets
